Application filed March 4, 1895. Serial No. 540,533. Term of patent 3½ years.

To all whom it may concern:

Be it known that I, ARCHIBALD FERGUSON REDDIE, a citizen of the United States, residing at the city of Philadelphia, in the county 5 of Philadelphia and State of Pennsylvania, have invented and produced a new and original Design for a Carpet or other Fabric, of which the following, taken in connection with the accompanying drawing, is a specification.

10 The effect represented in the accompanying drawing constitutes my design.

In the drawing, *a* is the body, *b* the border, and *a* and *b* the complete carpet.

15 My design may find expression in an endless variety of colors and combinations of colors and may of course be made to appear on the surface of Brussels, Wilton, velvet and other carpets.

20 The leading or characteristic feature of my design may be said to be the ornamental fig-

ure *c*, displayed upon a back-ground *d*, and in the drawing, associated with bands *e* and *f*, and with the draped rosette *g*.

What I claim as new, and desire to secure by Letters Patent, is—

- 25 1. In the design for a carpet the body *a*, substantially as shown.
2. In a design for a carpet the border *b*, substantially as shown.
3. The design for a carpet consisting of the 30 body *a*, and the border *b*, substantially as shown.

In testimony whereof I have hereunto signed my name in the presence of two witnesses.

ARCHIBALD FERGUSON REDDIE.
